(57) CLAIM

The ornamental design for a child's potty, as shown and described.

DESCRIPTION

FIG. 1 is a perspective view of the invention set forth herein;

FIG. 2 is front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines in the drawings are for illustrative purposes only and form no part of the claimed design.

The broken line immediately adjacent to the claim in FIG. 7 represent the bounds of the claim and form no part of the claimed design.

1 Claim, 7 Drawing Sheets
